UNITED STATES PATENT OFFICE

JOSEPH H. GOLDBERG, OF CHICAGO, ILLINOIS, ASSIGNOR TO CHICAGO CINEMA EQUIPMENT COMPANY, OF CHICAGO, ILLINOIS, A CORPORATION OF ILLINOIS

DESIGN FOR A CASING FOR A PICTURE-PROJECTION APPARATUS

Application filed June 7, 1929. Serial No. 31,581. Term of patent 14 years.

To all whom it may concern:

Be it known that I, JOSEPH H. GOLDBERG, a citizen of the United States, residing at Chicago, in the county of Cook and State of Illinois, have invented a new, original, and ornamental Design for a Casing for a Picture-Projection Apparatus, of which the following is a specification, reference being had to the accompanying drawing, forming part thereof.

The figure is a side elevation of a casing for a picture projection apparatus, showing my new design.

I claim:

The ornamental design for a casing for a picture projection apparatus, as shown.

JOSEPH H. GOLDBERG.
